UNITED STATES PATENT OFFICE.

THOMAS J. POLLARD, OF CRANSTON, AND LEWIS S. DARLING, OF PROVIDENCE,
RHODE ISLAND.

PIN JOINT.

1,404,218.

Specification of Letters Patent. Patented Jan. 24, 1922.

Application filed September 16, 1921. Serial No. 501,181.

To all whom it may concern:

Be it known that we, THOMAS J. POLLARD and LEWIS S. DARLING, citizens of the United States, residing at Cranston and Providence, respectively, in the county of Providence and State of Rhode Island, have invented certain new and useful Improvements in Pin Joints, of which the following is a specification.

10 Our invention relates to improvements in pin joints for use upon pins and brooches as used for ornamental purposes, and the principal object of our invention is to provide a pin joint inexpensive of construction, 15 simple in operation, and that can be readily secured to the body of the pin.

We accomplish this purpose by the device shown in the accompanying drawings, in which—

20 Figure 1 is a plan view of the back of the brooch showing the pin itself, and our improved joint secured to the back of the brooch;

Figure 2, a side view of the same, and

25 Figure 3, a plan view of the blank out of which the joint is constructed.

In Figure 1, 1 is a portion of the brooch with the back thereof toward the observer. 2, is the shank of the pin itself. The joint 30 before it is completed is shown in the blank form in Figure 3 and is comprised of a base with integral laterally slotted wings or ears 3—3 and a tongue 4 and a bifurcated or longitudinally slotted tongue 5, between said ears, as shown. This blank is struck in one piece by a single operation from suitable sheet metal. The blank is then bent upon the lines *a*, *b*, *c*, *d*, the members 3, 3, 4 and 5 being simply bent at approximately right 35 angles to the base. The tongue 5 of the blank is not bent until after the cross bar or head of the pin 2 has been inserted in the slots of the ears. When so inserted, the tongue 5 is then bent at right angles and the 40 inner wall of the slot in said tongue 5 serves as a support for the shank of the pin 2, for providing a proper tension when the pin engages the catch 7 commonly used on brooches, and at the same time this tongue 45 secures the pin safely within the lateral slots of the ears 3, 3. The joint is then fastened to the back of the brooch 1 by soldering or other equivalent method.

It will be seen from Figure 1 that the 50 form of pin used in connection with this

joint is what is known as a T-headed pin. The advantages of our improvement are simplicity, cheapness of construction, and security of the pin within the joint.

Having now described our invention, what 60 we claim and desire to secure by Letters Patent is:—

1. A pin joint comprising a base, laterally slotted ears upon the base, and a longitudinally slotted tongue upon the base between 65 the ears closing the entrances to the slots in said ears.

2. A pin joint comprising a base, laterally slotted ears upon the base, and a longitudinally slotted tongue upon the base between 70 the ears closing the entrances to the slots in said ears, the inner wall of the slot of said tongue terminating in position to serve as a support for the shank of a pin held by said joint prior to engagement of said pin with 75 the usual catch.

3. A pin joint comprising a base, laterally slotted ears upon the base, and a longitudinally slotted tongue upon the base closing 80 the entrances to the slots of said ears, said ears including upper portions overhanging the upper end of said tongue.

4. A pin joint comprising a base, laterally slotted ears upon the base, and a tongue upon the base between the ears having a 85 bifurcated free end and closing the entrances to the slots in said ears.

5. A pin joint comprising a base, laterally slotted ears upon the base, and a tongue upon the base between the ears having a 90 bifurcated free end and closing the entrances to the slots in said ears, the space between the bifurcations of the tongue communicating with the space between the ears for permitting free swinging movement of a pin 95 held by the latter and the tongue in the slots of the ears, and another tongue upon the base opposite the first named tongue forming a stop for the opening of said pin.

6. A pin joint comprising a base, laterally 100 slotted ears upon the base, and a tongue upon the base between the ears having a bifurcated free end and closing the entrances to the slots in said ears, the space between the bifurcations of the tongue communicating 105 with the space between the ears for permitting free swinging movement of a pin held by the latter and the tongue in the slots of the ears, and another tongue upon the base opposite the first named tongue forming a 110

stop for the opening of said pin, said first named tongue substantially contacting the front edges of the ears below their slots, and said ears including upper portions over 5 hanging the upper ends of the bifurcations of said first named tongue.

7. A pin including a pin member having a cross bar at one end, a joint member comprising a base having laterally slotted ears 10 thereon with the slots of said ears forming bearings for the ends of said cross bar, and a tongue upon the base having a bifurcated free end and retaining the cross bar within the slots of the ears, the space between the 15 bifurcations of said tongue communicating with the space between said ears for allowing swinging movement of the pin.

8. A pin including a pin member having a cross bar at one end, a joint member comprising a base having laterally slotted ears 20 thereon, with the slots of said ears forming bearings for the ends of said cross bar, and a tongue upon the base having a bifurcated free end and retaining the cross bar within 25 the slots of the ears, the space between the bifurcations of said tongue communicating

with the space between said ears for allowing swinging movement of the pin, the edge of the tongue between the bifurcations being located to form a stop for said pin prior to 30 the engagement of the latter with the usual catch whereby the pin is placed under tension.

9. A pin joint comprising a base, laterally slotted ears upon the base, and a longitudinally slotted tongue upon the base adapted to close the entrances to the slots of said ears.

10. A pin joint comprising a base, laterally slotted ears upon the base, and a longitudinally slotted tongue upon the base adapted to close the entrances to the slots of said ears, said ears including upper portions formed and adapted to overhang the upper end of said tongue.

In testimony whereof we affix our signatures in presence of two witnesses.
